UNITED STATES PATENT OFFICE.

WILLIAM G. WINSOR, JR., OF PAWTUCKET, RHODE ISLAND.

CHUTE-CLOSING GATE DEVICE.

Application filed January 6, 1926. Serial No. 79,699.

This invention relates to an improved construction of chute closing unit adapted to be connected to a chute or other conveyor for controlling the discharge opening therefrom; and the object of this invention is to provide a closing unit of this character which is adapted to be secured to the lower end or portion of the chute, the same being provided with a gate or closure member having a pair of side arms for pivotally suspending the gate to hang by gravity and swing into position to cover the discharge opening from the chute and to provide the gate with an operating handle by which it may be manipulated to control the flow through its discharge opening.

With these and other objects in view, the invention consists of certain novel features of construction, as will be more fully described, and particularly pointed out in the appended claim.

In the accompanying drawings:

Figure 1 is a side elevation partly in section illustrating my improved chute closing unit as applied to the lower end of the chute, the gate being shown in dotted lines in position to close the discharge opening therethrough.

Figure 2 is a perspective view of the chute closing unit showing the head member with the gate suspended to close the opening through the bottom thereof.

Figure 3 is a central sectional elevation of my improved head member and gate.

Figure 4 is a central longitudinal section through the head member and gate and showing the operating handle as attached to the gate.

Figure 5 is a perspective view of the gate and its operating handle detached from the head.

Figure 6 shows the detached elements which are employed for constructing one form of my improved head member of the closing unit.

It is found in the operation of closure members for chutes and the like, particularly those for controlling chutes employed in conducting such granular material as grain, sand, gravel, fine coal and the like, of advantage to provide a head member for controlling the opening through the chute which may be bolted in position over the end of the chute, the same being preferably provided with a circular or tapering bottom

wall plate through which a discharge slot or opening is formed, and to provide a gate member having elongated side arms which are pivotally connected to suspend the gate in position to swing under this circular body portion to close the opening therethrough. It will be seen that by this construction the weight of the material over the discharge opening is supported by the pivots on which the gate is hung whereby the frictional resistance in swinging the gate while under pressure of its load is reduced to the minimum and the natural tendency of this gate either with or without a load upon it is to swing back to its normal or closed position and when the material is being discharged through the opening it requires the minimum amount of pressure to swing the gate to cut off the flow and close the discharge opening; and the following is a detailed description of the present embodiment of my invention and showing one construction of chute closing unit by means of which these advantageous results may be accomplished:

With reference to the drawings, 10 designates the head member of my improved chute closing unit, which is herein shown as being formed of a bottom plate 11 curved on the arc of a circle and as being provided with a transverse elongated slot 12 through the bottom portion thereof.

The ends of this arcuate plate are closed by the end wall plates 13 connected thereto by a welding operation. Along the opposite upper edges 14 of this arcuate bottom plate, I connect the angle bars 15, preferably by a welding operation, also across the opposite end plates 13 I connect the angle bars 16 preferably by a welding operation and these angle bars are herein shown as being provided with bolt holes 17 through which bolts 18 may be passed for securing this closing head unit to the bottom of the chute 19.

In order to close this slotted discharge opening 12 in the bottom of the head member, I have formed a gate member 20 having a bottom closure plate 21 with elongated side arms 22 pierced at their upper ends as at 23 to receive the pivot pins 24.

These arms are set to straddle the end of the head-member and to suspend the closure plate 21 beneath the slot 12 therein, this plate being preferably sharpened or formed thin at its edges 22 so as to cut

through the granular material in moving the plate to closed position when the material is flowing rapidly through the discharge opening 12.

These pivot pins 24 are arranged to extend through the spacer plates 25 and through the walls 26 of the angle bars 16 and through the end walls 13 of the heads and in which position they may be screwed, welded or otherwise secured.

In order to provide simple means for operating this gate member, I have formed a loop-shaped handle 27 having side arms 28 secured to the opposite side arms 22 of the closure gate, which handle serves as a very convenient construction to be engaged by a hook or bar by the operator to either swing it from closure position to permit the material to flow from the chute and be as readily swung back to closed position to cut off this flow.

By suspending this gate on pivots at a point well above the discharge opening the gate is very easily swung from closing position even when carrying a full load upon it and is also very easily swung back when it is desired to cut off the flow.

By this construction the very short operating handle 27 may be employed which will not be in the way of teams, vessels, or other receptacles which it is desired to position beneath the chute.

I have herein shown and described my improved chute closing unit as being formed of sheet metal and the parts welded into posi-

tion, but it is understood that I do not restrict myself to this construction as the head-member may be formed complete as a single casting, if desired.

My improved unit is very simple and practical in construction and is effective in its operation and the discharge opening from a chute or other storing or conducting member may be nicely controlled and easily operated to be opened and permit a free discharge and as easily closed to shut off the flow of material therefrom.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A chute closing unit comprising a head member having side walls, and an arcuate shaped bottom wall provided with a discharge opening at its lowest point, a pair of arms pivotally mounted on said side walls, an arcuate gate member of the same curvature as the bottom wall disposed on the outer convex surface thereof and supported by said arms, and a bail-shaped operating handle attached to said arms and disposed below said arcuate gate.

In testimony whereof I affix my signature.

WILLIAM G. WINSOR, JR.
